UNITED STATES PATENT OFFICE.

JESSE A. JANES, OF METROPOLIS, ILLINOIS.

AUTOMATIC WATER-GAGE.

1,142,328.

Specification of Letters Patent. Patented June 8, 1915.

Application filed March 31, 1914. Serial No. 828,596.

To all whom it may concern:

Be it known that I, JESSE A. JANES, citizen of the United States, residing at Metropolis, in the county of Massac and State 5 of Illinois, have invented certain new and useful Improvements in Automatic Water-Gages, of which the following is a specification.

This invention relates to attachments for 10 steam generators and the like, for the purpose of denoting the height of water therein, more particularly to devices of this character in which a glass or like fragile transparent material is employed in which the 15 height of the water is visible, and has for one of its objects to provide a simply constructed device whereby in event of the breakage of the fragile member of the device, the steam and water will be automatically cut off and prevented from escaping 20 and held in cut-off condition until the broken or impaired portion is restored.

Another object of the invention is to provide a simply constructed device of this 25 character which may be readily attached to steam generators and like devices of various sizes in which steam or other medium under pressure is maintained, and without material structural change in the device or in the 30 generator.

Another object of the invention is to provide a simply constructed device which may be arranged in coactive relation with ordinary glass water gages without material 35 structural change in the glass supporting portion of the gage.

With these and other objects in view the invention consists in certain novel features of construction as hereinafter shown and described and then specifically pointed out in 40 the claims; and in the drawings illustrative of the preferred embodiment of the invention Figure 1 is an elevation partly in section of a portion of a steam generator with 45 one of the improved devices applied, a portion of the device being likewise in section. Fig. 2 is a transverse section on the line 2-2 of Fig. 1. Fig. 3 is a perspective view from beneath of the main balanced valve of 50 the device. Fig. 4 is a detached perspective view of the combined guide and stop.

Corresponding and like parts are referred to in the following description and indicated in all the views of the drawings by the same 55 reference characters.

The improved device comprises coacting

casings, each having a plurality of internal valve seats and connected by a tubular member of glass or like transparent material or substance, one of the casings adapted to be 60 connected in a generator above the water-line and the other casing connected in the generator below the water-line, so that the level or stage of the water is visible within the glass tube in the ordinary manner of a 65 water gage. The valve casings are precisely alike and the description of one will suffice for both.

The body of the casing is preferably 70 formed of two portions 10-11, the portion 10 having a valve seat 12 while the portion 11 is detachably connected to the portion 10 preferably by threading as shown at 13, and with a valve seat 14 in its threaded end and communicating at 15 with the interior of 75 the casing portion 10. The casing portion 10 is arranged to be connected, preferably 80 by means of a nipple 16 and clamp nut 16', in a steam generator or like receptacle for the liquid under pressure, one wall of which 85 is indicated conventionally at 17. The casing portion 10 is enlarged as represented at 18 between the seat 12 and the nipple connection 16 to provide free circulation for the steam or water, and is likewise provided 90 with an intermediate shoulder 19. A relatively large valve 20 is located within the portion 10 of the casing and adapted to engage the seat 12 and is provided with a 95 stem 21 extending into the smaller portion 95 of the casing. The stem 21 is formed with longitudinal steam passages in its sides, and is preferably formed triangular as represented in Fig. 2, so that the steam or water 100 will freely pass. Bearing upon the shoulder 19 is a stop member 22, preferably in spider-like form, to permit the free passage of steam or water, and operates to support one end of a spring 23, the opposite end of the spring bearing against the valve 20. The 100 stop member 22 is formed with passages or guideways to slidably receive the wings of the stem 21 as shown in Fig. 4.

The valve 20 is formed with radiating wings 24 at the side opposite from its seat, 105 so that the valve will not close against the nipple 16 when open and shut off the water or steam, as hereafter explained.

The threaded terminal 25 of the casing portion 10 where it engages the nipple 16 110 is sufficiently large to permit the valve 20 and its spring 23 and stop member 22 to be

inserted and removed through its larger threaded end, and likewise to permit the seat 12 to be properly ground.

The portion 11 of the casing is internally threaded to receive the threaded portion 23 of the stem 27 of a valve 28 which is adapted to be engaged with the seat 14 when the valve stem is operated. The portion 11 of the casing is provided with the usual cap 29 and turning wheel 30, to enable the valve 28 to be opened and closed from the exterior of the casing. Extending from the stem 27 in advance of the valve 28 is an extension 31 adapted to engage the outer end of the stem 21 of the valve 20 when the valve 28 is disposed upon its seat. By this means when the valve 28 is moved into its inner position the valve 20 will be forced from its seat, the object to be hereafter explained.

Each of the portions 11 of the casing is provided with a branch 32 and a "union" device 33 whereby a tubular glass member 34 is coupled to the oppositely disposed casings.

As before stated, one of the casings will be coupled into the generator 17 below the water-line while the other casing and its attachments will be coupled into the generator above the water-line, or in position to receive the steam, which is conducted into the upper end of the glass tube 34, while the water is conducted into the lower end of the glass tube, the member 34 thus serving the purpose of a water gage in the ordinary manner.

The valves 20, being relatively large and each provided with one of the springs 23, are forced from their seats by the action of the springs, and the steam or water under pressure permitted to flow equally around all sides of the valves 20 and thus balance the same and maintain them normally in open position, and permit the water and steam to flow freely into the opposite ends of the glass indicator member 34. Thus, while the generator is operating under normal conditions, the height of the water in the boiler will be accurately indicated. In event of the breakage or impairment of the glass member 34 the pressure will be suddenly reduced in the portions of the casings 10-11 externally of the valves 20, and the pressure of steam and water will instantly close the valves 20 and prevent the escape of the steam and water from the generator, and the valves will remain closed so long as the glass member 34 is detached. The valves 20 will not be disturbed until a new tube 34 has been disposed in place when the valves 28 will be closed by rotating the wheels 30 to cause them to engage the seats 14. At the same time the projections 31 will engage the stems 21 of the main valves 20 slightly in advance of the seating of the

valves 28. By this means the valves 20 will be forced from their seats to a limited extent before the valves 28 are closed, and thus permit the steam and water under pressure to flow around the valves 20 and impart pressure thereto equally from both sides, and thus balance the valves 20 as before described. The springs 23 greatly aid in this opening of the valves, and assist in maintaining equilibrium or balancing of the valve. The heads 30 of the valve stems 27 are then actuated to open the valves 28 and permit the steam or water to freely flow into the glass member 34 as before, the valves 20 being maintained perfectly balanced and permitting the steam or water to freely flow, as before stated.

The improved device is simple in construction, can be manufactured of any suitable material and any required size, and applied without material structural change to steam generators and like devices, and will automatically cut off the water or steam in event of the breakage of the gage and tube, thus preventing the escape of steam and water and holding the steam and water back in the boiler until the gage has been repaired.

Having thus described the invention, what is claimed as new is:

1. A device of the class described comprising a casing having valve seats spaced apart and with an internal annular shoulder intermediate the valve seats, said casing being formed with a guideway between the shoulder and one of said seats and enlarged between the shoulder and the other seat, a combined guide and stop device bearing upon said shoulder and having steam passages, a valve engaging one of said seats and having a stem formed with a plurality of lateral wings and movable through said guide device and engaging the guideway portion of the casing, and a spring bearing at one end against the combined guide and stop device and at the other end against the valve.

2. A device of the class described comprising a casing having a valve seat and an internal annular shoulder, said casing being enlarged between the shoulder and the seat and with a guideway at the opposite side of the shoulder, a combined guide and stop device bearing upon said shoulder and having steam passages, a valve engaging said seat and having a stem formed with a plurality of lateral wings and movable through said guide device and engaging the guideway portion of the casing, and a spring bearing at one end against the combined guide and stop device and at the other end against the valve.

3. In a device of the class described, a casing having an internal shoulder with a lateral chamber at one end, said casing be-

- ing enlarged between the shoulder and the chamber and having a valve seat at the juncture of the casing enlargements and the chamber and with a guideway at the 5 opposite side of the shoulder, a combined guide and stop device bearing upon said shoulder, a valve engaging said seat and having a stem formed with a plurality of lateral wings and movable through said 10 guide device and engaging the guideway portion of the casing, and a spring bearing at one end against the combined guide and stop device and at the other end against the valve.
- 15 4. A device of the class described, comprising a casing having an internal guideway at one end and enlarged into a chamber at the other end and with an enlargement between the chamber and the guideway, said

casing having a stop shoulder between the 20 guideway and the enlargement and another shoulder at the outer end of the chamber and a valve seat between the enlargement and the chamber, a valve adapted to engage the seat and with a stem at one side 25 formed with radial wings engaging the guideway of the casing and a plurality of radiating wings at the other side for engaging the last named shoulder of the chamber to prevent the body of the valve from 30 engaging the same, and a spring between the said stop shoulder and the valve.

In testimony whereof I affix my signature in presence of two witnesses.
